UNITED STATES PATENT OFFICE.

OSCAR R. CASSELL, OF NEW YORK, N. Y.

FLYING-MACHINE.

1,024,766.

Specification of Letters Patent. Patented Apr. 30, 1912.

Application filed April 8, 1910. Serial No. 554,217.

To all whom it may concern:

Be it known that I, OSCAR R. CASSELL, a citizen of the United States, residing at New York, in the county of New York and State of New York, have invented new and useful Improvements in Flying-Machines, of which the following is a specification.

This invention relates to composite flying machines of that type wherein provision is made for utilizing the buoying effect of a body of gas as well as the supporting effect of the dynamic reactions of the air upon the surfaces of a flotation plane.

The objects of the invention are to provide a machine of this character having a flotation surface forming both an aeroplane and an envelop for a gas reservoir, to provide novel means for holding the bags of a sectional reservoir in position, to provide novel means for buoying the machine if accidentally precipitated upon the surface of a body of water, and to provide novel means for supporting the machine upon the ground and steering the same while in flight.

With these and other objects in view, the invention consists of the features of construction, combination and arrangements of parts, hereinafter fully described and claimed, reference being had to the accompanying drawings, in which:

Figure 1 is a view in side elevation of a flying machine embodying my invention. Fig. 2 is a top plan view of the same. Fig. 3 is a sectional plan view taken substantially on the line 3—3 of Fig. 1. Fig. 4 is a vertical longitudinal section through a portion of the machine taken substantially on the line 4—4 of Fig. 2. Fig. 5 is a vertical transverse section taken on the line 5—5 of Fig. 1. Fig. 6 is a vertical transverse section taken on the line 6—6 of Fig. 1. Fig. 7 is a detail section taken on the line 7—7 of Fig. 4. Fig. 8 is a view in side elevation of the parts shown in Fig. 7. Fig. 9 is a detail view of the shifting weight employed for vertical steering and fore and aft balancing.

The machine comprises a substantially cigar-shape frame formed of curved longitudinal stringers 1 intermediately connected by a longitudinal series of vertically and transversely disposed bands or rings 2, the extremities of the stringers being attached to front and rear coupling bearings 3. Each coupling bearing and the adjacent portion

of the frame structure supports pairs of vertically disposed fins 4 and horizontally disposed fins 5, projecting respectively above and below and from opposite sides of the frame to prevent vertical and lateral deflection of the machine from its course and thus adapt it to travel in a straight line.

Arranged within the upper half of the frame and extending longitudinally thereof is a substantially semi-cigar-shape flotation body, the upper surface and sides of which conform to the contour of the upper surface of the frame, while the lower surface thereof is substantially flat or longitudinally curved. The said body consists of an outer shield or envelop 7 made of some suitable fabric and a sectional gas reservoir inclosed therein, said reservoir being formed of a longitudinal series of independent gas bags 8 arranged in abutting contact and each provided with a nipple 9 projecting downward through the base of the body whereby it may be filled with gas when occasion requires.

It will be understood from the foregoing description that the body forms an aerostat including a reservoir which may be filled with hydrogen or other gas lighter than air, and which is thus adapted to support a large proportion of the weight of the machine in the atmosphere. The lower flat or longitudinally curved surface of this aerostat also serves the function of a supporting plane or surface against which the air strikes in the travel of the machine and by its dynamic reactions thereon provides means for supplementing the buoying or lifting action of the aerostat to effectually sustain the entire weight of the machine and its occupants. By making the reservoir in sections, said reservoir may be conveniently replenished with gas and a new gas bag or section substituted for an imperfect one within a minimum period of time, and in the event of leakage of gas from or damage to any one of the sections the efficiency of the remaining sections will remain unimpaired. Preferably, a vertical fin or vané 10 is provided centrally of the upper surface of the aerostat for co-operation with the fins 4 and 5 to prevent deflection of the machine from its course. A belt 11 of cork or other suitable material buoyant in water is preferably provided within the body 6 and extended around the same to insure flotation and the safety of the machine and its occupants.

in the event that the machine should be precipitated into a body of water. A ladder 12 is provided for use under such conditions to enable the occupants of the machine to climb 5 to the top or unsubmerged portion of the body 6. The ladder 12 extends upwardly from a car, platform or receptacle 13 arranged centrally of the frame and at the lowest portion thereof. This car or receptacle is preferably 10 substantially boat-shaped and forms a support for the aviator and passengers, if any, the driving motor and the steering and controlling devices. The propelling mechanism comprises front and rear pulling and pushing propellers 14 and 15 mounted upon the corresponding end of a longitudinally extending shaft 16 journaled in the coupling bearings 3 and in suitable bearings 17 carried by cross braces connecting the sides of 15 certain of the frame rings or bands 2. As shown, the shaft is connected intermediate of its length by a sprocket drive chain 18 with a motor 19 mounted on the car, but any suitable transmission gearing for driving the shaft from the motor may be employed. Secured to the frame band beneath the under side of the body 6 are inclined flat or curved aeroplanes 20 and 21, disposed in tandem relation, for further promoting 20 sustentation of the machine.

The machine is mounted at front and rear upon correspondingly constructed wheeled trucks 22, designed to support the machine upon the surface of the ground and to be employed in an obvious manner in launching and landing. Each of these trucks is carried by an axle or stem 23 journaled for oscillation in a bearing 24 pivoted upon a bracket 25 carried by the frame for fore 25 and aft swinging movement, each truck thus being adapted to turn in its bearing to adjust the wheels laterally for steering purposes and to swing with its bearing longitudinally of the machine for a purpose hereinafter described. A cross bar 25 is arranged upon the upper end of each axle 23 and the cross bars of the two trucks are coupled by chains or other connections 26 by which said trucks may be turned in unison 40 through the medium of suitable operating means, not shown, arranged to transfer motion to said chains. Each truck is connected above and below the bearing to adjacent portions of the frame by diverging springs 55 27 and 28, which normally tend to hold the trucks in a neutral position and return the same to such position after each lateral steering movement thereof. In making a landing or descent it is desirable to adapt the trucks to have a cushioning action on contacting with the surface of the ground. This action is secured by the capability of the trucks to swing rearwardly with their 60 bearings, which movement is limited by the springs 28, whereby the cushioning action is

secured. A vertical rudder 29 is mounted upon each truck, so that by turning the trucks when the machine is in flight the latter may be steered in a horizontal plane.

In order to place the center of gravity of the machine at a low point as well as to provide means for vertical steering, a shifting weight 30 is employed and connected with the lower stretch of an endless belt 31 extending longitudinally beneath the frame and under the car 13 and passing around suitable guide pulleys 32 on said frame. The weight is normally arranged in the vertical center line of the machine coinciding with the center of gravity and is adapted to be shifted by the movement of the belt to a position in front or rear of said center line to tilt the machine downward or upward in a fore and aft direction, whereby the ascent and descent of the machine may be readily controlled. To shift the belt a lever 33 is employed, which is mounted upon the car 13 and connected with the upper stretch of the belt, as clearly shown in Fig. 4.

From the foregoing description, taken in connection with the drawings, it will be obvious that in the event of the stoppage of the motor or reduction of the speed of the machine from any other cause below that required to sustain it in flight the buoyant body 6 will still afford sufficient support to prevent the machine from dropping suddenly to the ground and sustain it so that it will descend slowly and easily, without liability of injury to the machine or danger to the aviator. Other important advantages will be apparent without recitation.

Having thus described my invention, I claim:

1. A flying machine embodying an elongated substantially cigar-shaped frame, an aerostat occupying the upper half of the frame, said aerostat comprising a sectional gas reservoir and a casing therefor, the lower surface of said casing forming an aeroplane, aeroplanes arranged in the lower portion of the frame in front and rear of the transverse center thereof, said aeroplanes being arranged in tandem relation and inclined downwardly and rearwardly, a car arranged within and supported by the frame below the juxtaposed ends of said tandem aeroplanes, coupling members connecting the frame elements at the front and rear of the frame and provided with stability fins and bearings, a shaft journaled in the frame and coupling bearings and extending longitudinally between the aerostats and aeroplanes, propellers upon the front and rear ends of the shaft, a motor on the car, and gearing for driving the shaft from the motor.

2. A flying machine embodying a substantially cigar-shaped frame composed of

curved longitudinal stringers and a series of transversely arranged bands connecting and reinforcing the same, coupling bearings connecting the front and rear converging 5 ends of the stringers, vertically and longitudinally disposed fins at each end of the frame held by the coupling bearings, adjacent ends of the stringers and contiguous bands, a flotation body occupying the 10 upper half of said frame and extending longitudinally thereof, said body forming a

gas reservoir and an aeroplane surface at the base thereof, a shaft extending beneath said surface and journaled in said coupling, propellers mounted upon said shaft, and 15 means for driving the shaft.

In testimony whereof I affix my signature in presence of two witnesses.

OSCAR R. CASSELL.
